United States Patent Office

Des. 185,786
Patented Aug. 4, 1959

185,786

HOLDER FOR AN ELECTRIC SHAVER

Jan van der Togt, Zwijsdrecht, Netherlands, assignor to Tomado N.V., Dordrecht, Netherlands

Application February 28, 1958, Serial No. 49,839

Term of patent 14 years

(Cl. D4—3)

FIG. 1

FIG. 3

Fig. 1 is a top perspective view of a holder for an electric shaver, showing my new design;

Fig. 2 is a front view in elevation of said holder, and
Fig. 3 is a side view in elevation of said holder.

The broken line portions of the disclosure are depicted for illustrative purposes only.

I claim:

The ornamental design for a holder for an electric shaver, as shown and described.
